UNITED STATES PATENT OFFICE.

ROBERT L. FRINK, OF BELLEVERNON, PENNSYLVANIA, ASSIGNOR TO WINDOW GLASS MACHINE COMPANY, OF PITTSBURG, PENNSYLVANIA, A CORPORATION OF NEW JERSEY.

CRANE MECHANISM.

No. 907,141.

Specification of Letters Patent.

Patented Dec. 23, 1908.

Application filed March 8, 1906. Serial No. 304,882.

To all whom it may concern:

Be it known that I, ROBERT L. FRINK, of Bellevernon, Fayette county, Pennsylvania, have invented a new and useful Crane Mechanism, of which the following is a full, clear, and exact description, reference being had to the accompanying drawings, forming part of this specification, in which—

Figure 1 is a side elevation of crane mechanism embodying my invention illustrating the same as used for handling drawn glass cylinders; Fig. 2 is an enlarged side view of the cylinder clamping or carrying devices and their operating mechanism; Fig. 3 is an end view of the same; Fig. 4 is a plan view of the same; Fig. 5 is an end elevation of the movable carriage and the parts carried thereby; Fig. 6 is a plan view of the same; and Fig. 7 is an enlarged side view of a portion of the crane mechanism.

My invention has relation to crane mechanism which has been especially designed for use in handling drawn glass cylinders, but which is useful for various other purposes, as will be readily understood from the following description:

My invention consists in the novel construction, arrangement and combination of parts all substantially as hereinafter described and pointed out in the appended claims.

In the drawings, the numeral 2 designates the bridge of a crane which is movable on the tracks 3, and on which is mounted a transversely movable carriage 4. Pivoted at 5 to a depending portion 4' of the frame of the carriage 4 is a lever or lever frame 6, to the outer end portion of which is pivoted at 7 a lifting beam 8. The opposite end of the lever frame 6 is counterweighted as shown at 9, 9, and also carries two sector gears 10, the teeth of which mesh with pinions 11 on a shaft 12 mounted transversely in the crane carriage 4. The shaft 12 is arranged to be rotated by means of a motor 13 mounted on the carriage 4, through the worm gear connections 14. Journaled in the lever frame 6 is a longitudinal screw shaft 15 on which is mounted a movable head 16 connected by a link 17 with a depending portion 18 of the lifting beam 8. The shaft 15 is connected by gears 15^a with an actuating motor 15^b which is supported by the lever frame 6.

Journaled in bearings 18^a carried by a frame 19 at the end of the lifting beam 8 are

two vertical rock shafts 20, to which are secured the clamps 21 which are designed to embrace the drawn glass cylinder indicated at A in Fig. 1. This cylinder is shown as suspended above a glass pot B of glass drawing apparatus C. The clamps 21 consist of frame portions 21^a having grips 22 which are preferably composed of pieces of flexible asbestos wire cloth, or other yielding material of a refractory nature. The rock shafts 20 are connected by toggle links 23 with a nut 24 which has a screw-threaded connection with a shaft 25, which is journaled on the lifting beam 8, and is coupled at 26 to an actuating motor 27 which is also mounted on said beam.

Supposing the mechanism described to be used for the purpose of removing the drawn glass cylinder A from the glass drawing apparatus, and transferring it to any desired part of the factory, and placing it in horizontal position, the operation is as follows:—The parts being in the position shown in Fig. 1, the motor 27 is started, thereby actuating the shaft 25 and moving the nut 24 thereby, through the toggle links 23, close the gripping jaws 21 upon the cylinder A. The cylinder is now supported by the lifting beam 8 and lever frame 6, and may be disconnected from the drawing apparatus, and the crane bridge 2 moved to any desired position on the tracks 3. By now operating the motors 13 and 15^b, and at the same time moving the carriage 4 backwardly on the crane bridge 2, the cylinder may be turned into horizontal position and lowered, as shown by the dotted lines in Fig. 1, the motor 15^b operating through the screw shaft 15 to move the head 16 to thereby swing the lifting beam 8 on its pivots 7, while the operation of the motor 13 swings the entire mechanism upon the center 5, as will be readily understood. The counterweights 9 which are connected to the rear end of the lever frame 6, are of sufficient weight to practically counterbalance the weight of the arms 6, 8, 17, and of the gripping mechanism together with the weight of the lifting beam 8 and the parts carried thereby.

It will be apparent that instead of providing the lifting beam 8 with the gripping mechanism especially adapted for clamping and holding drawn glass cylinders, the said beam may be provided with lifting or supporting devices of various kinds to adapt

the mechanism for use in handling various objects which it is desired to move from one position to another.

The advantages of my invention consist 5 in the simplicity of the construction, and in the ease and rapidity with which the objects to be handled may be taken hold of and carried and moved into any desired position.

Various changes may be made in the de- 10 tails of construction and arrangement of the parts without departing from the spirit and scope of my invention, since

What I claim is:—

1. In crane mechanism, a movable carriage, a jointed lifting and carrying device pivoted to the carriage arranged to engage a vertical cylinder or similar object, means for moving said device upon its pivot to bring the cylinder into horizontal position, and 15 means for separately moving one of the jointed members of said device; substantially as described.

2. In crane mechanism, a movable crane bridge, a carriage mounted for transverse 20 movement on the bridge, a lever frame pivoted to the carriage, a lifting beam pivoted to the lever frame and having mechanism for engaging a vertical cylinder or similar object, and means for actuating said crane 25 and beam, and also for moving the carriage; substantially as described.

3. In crane mechanism, a movable carriage, a lever frame pivoted thereto, a lifting beam pivotally connected to the lever frame 30 and having mechanism for engaging a vertical cylinder or similar object, and means for separately actuating the frame and beam; substantially as described.

4. In crane mechanism, the combination 35 with a movable carriage of a pivoted and jointed lifting frame carried thereby said frame having means for engaging a vertical cylinder or similar object, and means for swinging the frame to lower the object into 40 horizontal position; substantially as described.

5. In crane mechanism, the combination 45 with a movable crane bridge, and a carriage movable on the bridge, of a counterweighted jointed lifting and carrying device pivoted 50 to the carriage, and means for actuating the same; substantially as described.

6. In crane mechanism, a carriage, a counterweighted lever frame pivoted to the carriage, a motor geared to said frame, a lifting beam pivoted to the lever frame, and a motor for moving said beam; substantially as 55 described.

7. In crane mechanism, a carriage, a lever pivoted thereto to swing in a vertical plane, 60 a motor geared to said lever, a lifting beam pivotally connected to the lever and having grippers arranged to engage a vertical cylinder, a motor, and operating connections

between the motor and the beam for swing- 65 ing the beam independently of the lever; substantially as described.

8. In crane mechanism, a carriage, a lever pivoted thereto, a motor device for actuating the lever, a lifting beam pivotally connected 70 to the lever and having grippers arranged to engage a vertical cylinder, a motor carried on the lever, and connections between the motor and the lifting beam; substantially as described.

9. In crane mechanism, the combination 75 of a carriage, a lever pivoted thereto and having a counterweighted end portion carrying toothed sectors, a motor geared to the sectors, a lifting beam pivotally connected 80 to the opposite end portion of the lever, a motor mounted on the beam, a movable cross-head actuated by the motor, and a connection between the head and the lifting beam; substantially as described.

10. In crane mechanism a pivoted lifting beam and means for actuating it, a support mounted on said beam at an angle thereto, and clamping devices on said support adapted to engage a vertical cylinder, sub- 85 stantially as described.

11. In crane mechanism, the combination 90 of a pivoted lifting beam and means for moving the same, of pivoted clamps carried by a support extending at an angle to and mounted on the beam, and means for opening and closing the clamps; substantially as described.

12. In crane mechanism, the combination 95 with a lifting beam and means for actuating the same, of pivoted clamps carried by the beam, and having yielding clamping members; substantially as described.

13. In crane mechanism, the combination 100 with a lifting beam and means for actuating the same, of rock shafts carried by the beam, a motor supported on the beam, connections between the motor and the rock shafts, and clamps carried by the rock shafts; substantially as described.

14. In crane mechanism, a movable carriage, a movable beam supported thereby, rock shafts carried on the beam, clamps carried by the rock shafts, a movable nut or head, and means for actuating the same, and 110 connections between the nut or head and the rock shaft; substantially as described.

15. In crane mechanism, a lifting clamp having a yielding or flexible clamping surface formed of a slow-burning material of 115 low heat conductivity; substantially as described.

In testimony whereof, I have hereunto set my hand.

ROBERT L. FRINK.
